(57) **CLAIM**

The ornamental design for a hand-held remote-control device and dock, as shown and described.

DESCRIPTION

FIG. 1 is a right side, top perspective view of a first embodiment of a hand-held remote-control device showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a right side, top perspective view showing the first embodiment of the hand-held remote-control device disposed within a dock

FIG. 9 is a front elevation view of the dock having the first embodiment of the hand-held remote-control device disposed therewithin;

FIG. 10 is a rear elevation view of the dock;

FIG. 11 is a top plan view of the dock having the first embodiment of the hand-held remote-control device disposed therewithin;

FIG. 12 is a bottom plan view of the dock having the first embodiment of the hand-held remote-control device disposed therewithin;

FIG. 13 is a left side elevation view of the dock having the first embodiment of the hand-held remote-control device disposed therewithin;

FIG. 14 is a right-side elevation view of the dock having the first embodiment of the hand-held remote-control device disposed therewithin;

FIG. 15 is a right side, top perspective view of a second embodiment of a hand-held remote-control device showing my new design;

FIG. 16 is a front elevation view thereof;

FIG. 17 is a rear elevation view thereof;

FIG. 18 is a top plan view thereof;

FIG. 19 is a bottom plan view thereof;

FIG. 20 is a left side elevation view thereof;

FIG. 21 is a right side elevation view thereof;

FIG. 22 is a right side, top perspective view showing the second embodiment of the hand-held remote-control device disposed within a dock

(Continued)

FIG. 23 is a front elevation view of the dock having the second embodiment of the hand-held remote-control device disposed therewithin;

FIG. 24 is a rear elevation view of the dock;

FIG. 25 is a top plan view of the dock having the second embodiment of the hand-held remote-control device disposed therewithin;

FIG. 26 is a bottom plan view of the dock having the second embodiment of the hand-held remote-control device disposed therewithin;

FIG. 27 is a left side elevation view of the dock having the second embodiment of the hand-held remote-control device disposed therewithin; and,

FIG. 28 is a right-side elevation view of the dock having the second embodiment of the hand-held remote-control device disposed therewithin.
